UNITED STATES PATENT OFFICE

GEORGE EATON, OF CLEVELAND, OHIO

DESIGN FOR AN ELECTRIC TOASTER

Application filed March 10, 1930. Serial No. 34,815. Term of patent 14 years.

To all whom it may concern:

Be it known that I, GEORGE EATON, a subject of Great Britain, residing at Park Lane Villa, Park Lane Avenue and East 105th Street, in the city of Cleveland, county of Cuyahoga, and State of Ohio, have invented a new, original and ornamental Design for an Electric Toaster, of which the following is a specification, reference being had to the accompanying drawings, forming part thereof.

Fig. 1 is a side elevation and Fig. 2 is an end

elevation of an electric toaster showing my new design.

The design consists of an electric toaster having a frame and a door upon which appears a grilled ornamentation.

I claim:

The ornamental design for an electric toaster as shown and described.

GEORGE EATON.
